UNITED STATES PATENT OFFICE.

WILLIAM J. JENKS, OF NYACK, NEW YORK.

ELECTRIC CUT-OUT.

SPECIFICATION forming part of Letters Patent No. 437,362, dated September 30, 1890.

Application filed June 16, 1890. Serial No. 355,669. (No model.)

To all whom it may concern:

Be it known that I, WILLIAM J. JENKS, a citizen of the United States, residing at Nyack, in the county of Rockland and State of New York, have invented an Improved Cut-Out Apparatus for Electrical Instruments, of which the following is a specification.

My invention relates to devices designed to protect electrical instruments—such as telephone-instruments, telegraph-instruments, fire-alarm instruments, burglar-alarms, &c.—and to protect the users thereof from the harmful effects of high potential or other currents due to a cross-connection with other circuits or other causes.

The object of my invention is to produce an apparatus which shall cut out the instrument to be protected promptly and certainly, and thus largely reducing the danger of burning out the instrument, or giving dangerous shocks to the user, or of setting fire to the building into which the circuit may extend.

It has been found that various devices, more especially when applied to grounded circuits, have to a certain extent protected the circuits and instruments of the kinds mentioned against the heating effects of currents of abnormal ampères; but serious difficulties have been realized in their application. In the effort to secure this protection by means of fusible strips, for example, it has been found necessary to make the strips so sensitive that they have been liable to accidental rupture from mechanical or electrical causes.

It also happens, especially in metallic circuits normally insulated from the earth and used for fire-alarm, telephone, and similar purposes, that, owing to a cross with an electric light or power conductor such metallic circuit is raised to a high potential relative to the earth, or to some other conductor with which there may be danger of contact, or to which an escape may at any time occur. A circuit thus charged to a high potential may become a source of danger by its tendency to destroy the instruments connected with it, to set fire to surrounding materials, or to give shocks to the user. In such a case there may be no flow of current from the insulated metallic circuit, and therefore no device depend-

ing wholly upon the flow of current has proved sufficient under such conditions.

My present invention consists in providing a branch or shunt containing a potential circuit-controller—such, for example, as described in my patent, No. 428,564, dated May 20, 1890—between the instrument to be protected and the line, with a magnet directly in the main line and operating a shunting or circuit opening switch, and the combination with the above devices of a fusible or thermal cut-out, so adjusted as to operate only on the passage of a current stronger than that required to operate the magnet, and in other combinations, as hereinafter described and claimed.

The magnet being directly in the main line can be kept normally charged to a partial extent, but not enough to attract its armature, by the current on the line—as, for example, in closed-circuit fire-telegraph systems—and can be made to operate its switch by a slight increase of current, thus making a more delicate apparatus than one in which the operating-magnet is placed in a normally-open ground branch. The necessary increase of current to operate the switch is immediately furnished when the potential circuit-controller is broken down, as described in the above patent. If the dangerous rise in potential on the circuit is of only short duration all that is necessary is to cut out the instrument to protect it from injury. This is accomplished by the potential circuit-closer. If a current then flows of, say, one ampère, (which is too heavy for the telephone-coil,) the magnet will be energized, thereby operating the switch to open the line or to form a short circuit to earth. In the latter case if the current increases, say, to two ampères, the fusible cut-out will be operated and sever the line. It sometimes happens also that the distance between the magnet and its armature gets too great by a disarrangement of the apparatus, or the armature becomes locked by rust or some impediment, and in that case the fusible cut-out will operate irrespective of the magnet before the current becomes of sufficient strength to destroy the potential circuit-closer.

In the accompanying drawings, which illus-

trate my invention, Figure 1 is a diagrammatic view of one embodiment of the invention in which the switch operated by the magnet breaks the main line. Figs. 2 and 3 are 5 modifications in which the switch closes a short circuit.

In Fig. 1 the apparatus is shown as applied to a grounded telephone-line 1. 2 is the telephone apparatus. 3 is a branch or shunt leaving the line between the telephone and the line, said branch containing a potential circuit-closer 4. 5 is a magnet placed directly in the main line on the line side of branch 3. The armature of this magnet controls a switch, 15 which in this instance opens and leaves open the main line, and the armature-lever forms a part of the switch. 6 is a fusible cut-out in the line. The circuit-controller 4, which consists, preferably, of two plates very near 20 together, preferably separated by a perforated disk of mica, and inclosed in an air-tight case, is adjusted to be operated or broken down on a definite rise of potential in the circuit and before the magnet 5 is sufficiently energized 25 to attract its armature. When the circuit-controller is thus broken down a low-resistance path is formed to earth. If then a current of sufficient volume to injure the telephone flows over the line the magnet will attract its armature and open the circuit. A 30 cross is supposed to exist at 11, between the telephone-circuit and another circuit carrying dangerous currents.

In Fig. 2 the invention is shown applied to a metallic circuit 1 1'. 2 is the instrument to be protected, 3 3' branches or shunts from the line between the instrument and the magnets 5 5' which operates the switches, which are composed of the armature-levers and the 35 springs 7 and co-operating contacts 8. The operation of this arrangement is as follows: Upon a definite rise of potential the circuit-controller 4 allows the passage of current, thereby creating a low-resistance path and 40 shunting the instruments to be protected. Then if sufficient current flows over the line to earth the armature of magnet 5 or 5' is attracted, releasing spring 7, which snaps against contact 8, closing the short circuit to 45 ground. If the current is momentary only, or is of comparatively low ampères—say, one ampère—the spring can at once be replaced and the system will be in condition for use; but should a heavier current flow over the line 50 the fusible cut-out 6 would be melted and the line entirely opened at that point. If desired, a signal may be placed at 9 to indicate the 55 operation of the switch, and this signal may continue to operate until the fusible cut-out 60 opens the line.

In Fig. 3 the armature of the switch-magnet is not normally in the circuit, but when the armature is attracted the armature-lever snaps over the hook 10 and closes a short circuit to ground G, around both the magnet 65

and circuit-controller, as well as the telephone or other instruments. The operation of this modification will be clear without further description.

It is evident that the location and form of some of the parts may be varied to a considerable extent without departing from the invention.

In my application No. 340,703, filed February 17, 1890, I have claimed, broadly, the combination of a circuit, including an instrument to be protected, a circuit-opening device wholly in the main circuit between the line and instrument, a branch or shunt between the circuit-opening device and instrument 75 containing electrically-disconnected circuit-terminals operated by a definite rise in potential before operation of said circuit-opening device, and also specifically the combination of a circuit, including an instrument to be protected, a fusible cut-out wholly in the main circuit and between the line and instrument, a branch or shunt between the cut-out 80 and instrument containing electrically-disconnected circuit-terminals, and these combinations are not claimed, broadly, in the present application.

Having thus described my invention, what I claim is—

1. The combination of a circuit, including 95 an instrument to be protected, a circuit-opening device wholly in the main circuit, a magnet directly in the main line for operating the same, and a branch or shunt between the instrument to be protected and the 100 circuit-opening device, containing electrically-disconnected circuit-terminals operative by a definite rise of potential before the operation of said switch-magnet, substantially as described.

2. The combination of a circuit, including 105 an instrument to be protected, a switch and an operating-magnet therefor, both directly in the main line, a branch or shunt between the instrument and switch containing electrically-disconnected circuit-terminals operative on a definite rise of potential before operation of said magnet, and a short circuit for the instrument closed by said switch, but not including said terminals, substantially as 110 described.

3. The combination, with an instrument to be protected, a magnet in the main line, a branch or shunt between the instrument and line containing a potential circuit-closer operative on a definite rise in potential before operation of the magnet, a short circuit closed by the magnet and maintaining the circuit complete through a second cut-out directly in the main line, said cut-out being operative by 115 a current of greater ampères than the magnet, substantially as described.

4. The combination, with an instrument to be protected, of a switch in the main line, an operating-magnet therefor, a branch or shunt 120

between the instrument and line containing a potential circuit-closer operative on a definite rise of potential before operation of the magnet, a short circuit closed by the magnet and containing an alarm, and a second cut-out for completely severing the line on a further increase of current, substantially as described.

This specification signed and witnessed this 6th day of June, 1890.

WILLIAM J. JENKS.
